UNITED STATES PATENT OFFICE.

LENA B. ASHBY, OF HOMER, KENTUCKY.

SANITARY SPUTUM-CUP.

1,266,758.

Specification of Letters Patent. Patented May 21, 1918.

Application filed October 16, 1917. Serial No. 196,956.

To all whom it may concern:

Be it known that I, LEONA B. ASHBY, a citizen of the United States, residing at Homer, in the county of Logan, State of Kentucky, have invented certain new and useful Improvements in Sanitary Sputum-Cups; and I do hereby declare the following to be a full, clear, and exact description of the invention, such as will enable others skilled in the art to which it appertains to make and use the same.

This invention relates to new and useful improvements in sanitary receptacles and particularly to sputum cups.

One object of the present invention is to provide a cup of this character wherein the destructible inner cup or lining is rendered more easy of removal and without danger of contact with the interior or contents of the said lining.

Another object is to provide a device of this character which includes a sanitary and waterproof lining for the closure of the cup, and novel means for holding said lining in place and rendering the same readily removable.

Other objects and advantages will be apparent from the following description when taken in connection with the accompanying drawing.

In the drawing:

Figure 1 is a side elevation of a sputum cup made in accordance with my invention.

Fig. 2 is a top plan view of the same.

Fig. 3 is a vertical transverse sectional view taken on the line 3—3 of Fig. 2.

Fig. 4 is a horizontal sectional view taken on the line 4—4 of Fig. 1.

Fig. 5 is a vertical sectional view showing the method of removing the lining from the cup.

Fig. 6 is a sectional view through the cover of the cup showing the manner of removing the lining thereof.

Referring particularly to the accompanying drawing, 10 represents a cup which is preferably formed from aluminum and has the rounded and heavily weighted bottom 11 whereby the said cup will quickly and easily right itself should it be overturned. A flanged cover 12 is hinged to the upper end of the cup at 13, said cover being provided with a spring latch 14 which engages in a depression 15 in the upper forward portion 55 of the cup. The cover is formed centrally

with an opening 16 and disposed vertically through this opening is a stem 17, said stem having a knob 18 on the upper end and a pair of oppositely extending horizontal arms 19 on the other end. Encircling the stem, 66 between the knob and the upper face of the cover, is a coil spring 20 which normally urges the stem upwardly so that the arms 19 will be held firmly against the lower face of the cover. A sanitary and waterproof 65 disk 21 is disposed within the cover and is formed centrally with an elongated slot 23. Through this slot the said arms 19 are arranged to be passed after the lining or disk has been properly placed within the cover. 70 When so positioned, the knob is grasped and pushed downwardly so as to dispose the arms 19 below the said disk 21, when the stem is turned to dispose the arms transversely of the slot when the disk will be firmly held in 75 the cover by the upward pressure exerted by the spring 20. When it is desired to remove the lining of the cover the stem is turned to present the arms 19 within the slot of the disk, whereupon the operator pushes 80 his finger through the opening 24, in the cover at one side of the center, and thus disengages the disk.

In diametrically opposite sides, adjacent the upper end of the cup, there are formed 85 the openings 25 through which the fingers of the hand are adapted to be inserted to remove the water-proofed paper lining or cup 28 which is disposed snugly within the cup 10. It is intended that the paper cup 90 shall fit snugly within the cup 10 to such an extent that it will be practically impossible to insert any instrument between the lining and cup. Furthermore, this tends to render the device more sanitary for the reason that 95 it obviates the necessity of bringing the fingers in contact with the interior of the lining of the cup. When the fingers are pushed through the openings 25, the upper portion of the lining will be collapsed or pinched 100 together, thereby rendering it easy to grasp the collapsed end with the finger and thumb and quickly remove the lining from the cup 10. In this way the fingers do not come in contact with the interior of the cup and 105 cover, nor the contents thereof.

It will, of course, be understood that the cover is raised when the device is to be used and again closed and latched after use.

While I have shown the cup of circular 110

cross-section, it will be understood that the same may be elliptical in cross section to more readily fit into the pocket of the user.

The provision of the weighted bottom is especially useful in hospitals or sick rooms to prevent the upsetting of the contents of the cup should the cup be overturned. In the event that the cup is overturned the same will immediately right itself, as will be readily understood.

What is claimed is:

1. A sputum cup including a receptacle open at its top, a close-fitting cover for the top of the receptacle, and a removable collapsible lining within the receptacle, said receptacle having openings therein at diametrically opposite points and below its upper edge through which the fingers of the user may be inserted and the upper portion 15 of the lining collapsed so that said upper portion may be grasped upon its outer surface and removed from the receptacle.
2. A sputum cup including a receptacle having a removable collapsible lining fitting

snugly therein, said receptacle having finger 25 receiving openings in diametrically opposite points for the reception of the fingers of the user to collapse the upper portion of the lining without touching the interior thereof, a movable cover for the receptacle, a re- 30 movable lining for the cover, means for holding the lining in the cover, said cover having a finger opening for permitting the removal of the lining.

3. A sputum cup including a receptacle, a 35 removable collapsible lining for the receptacle, the receptacle having finger receiving openings for facilitating the collapse and removal of the lining without touching the interior of the lining, and a movable cover 40 having a removable lining, and means for holding the lining therein.

In testimony whereof, I affix my signature in the presence of two witnesses.

LENA B. ASHBY.
